US00D922026S

(12) **United States Design Patent** (10) **Patent No.:** **US D922,026 S**
(45) **Date of Patent:** **** Jun. 15, 2021**

(54) **RIB PET TREAT**

(71) Applicant: **Spectrum Brands, Inc.**, Middleton, WI (US)

(72) Inventors: **Gregory van Eyk**, Christiansburg, VA (US); **Casey Sims**, London (GB); **Todd Palmer**, O Fallon, MO (US)

(73) Assignee: **Spectrum Brands, Inc.**, Middleton, WI (US)

(**) Term: **15 Years**

(21) Appl. No.: **29/749,380**

(22) Filed: **Sep. 4, 2020**

Related U.S. Application Data

(62) Division of application No. 29/703,991, filed on Aug. 30, 2019, now Pat. No. Des. 898,326, which is a division of application No. 29/672,111, filed on Dec. 3, 2018, now Pat. No. Des. 858,931.

(57) **CLAIM**

The ornamental design for a rib pet treat, as shown and described.

DESCRIPTION

FIG. 1 is a front, top, and left side perspective view of a rib pet treat according to the new design;

FIG. 2 is a back, top and right side perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in FIGS. 1-8 illustrate portions of the rib pet treat that form no part of the claimed design.

1 Claim, 6 Drawing Sheets
